(57) **CLAIM**

I claim the ornamental design of a handle grip, as shown and described.

DESCRIPTION

FIG. 1 is a perspective view of a grip for a golf club having my new design;

FIG. 2 is a top, plan view of the grip of FIG. 1;
FIG. 3 is a bottom, plan view of the grip of FIG. 1;
FIG. 4 is a front, side view of the grip of FIG. 1, the rear, side view being the same;
FIG. 5 is a left-side view of the grip of FIG. 1, the right-side view being the same;
FIG. 6 is a cross-sectional view taken along line VI—VI of FIG. 4;
FIG. 7 is a cross-sectional view taken along line VII—VII of FIG. 4;
FIG. 8 is a perspective view in reduced scale of the grip in use with a gold club;
FIG. 9 is a perspective view of a second embodiment of a grip for an article such as a two-wheeled trolley having my new design;
FIG. 10 is a top, plan view of the grip of the second embodiment of FIG. 9;
FIG. 11 is a bottom, plan view of the grip of FIG. 9;
FIG. 12 is a front, side view of the grip of the second embodiment of FIG. 9, the rear, side view being the same;
FIG. 13 is a left-side view of the grip of the second embodiment of FIG. 9, the right-side view being the same;
FIG. 14 is a cross-sectional view taken along line XIV—XIV of FIG. 12;
FIG. 15 is a cross-sectional view taken along line XV—XV of FIG. 12; and,
FIG. 16 is a perspective view in reduced scale of the grip of the second embodiment in use with a two-wheeled trolley.
The broken lines shown in FIGS. 8 and 16 are for illustrative purposes only and form no part of the claimed invention.
